UNITED STATES PATENT OFFICE.

WILFRED B. GODDARD, OF SAN FRANCISCO, CALIFORNIA, ASSIGNOR TO THOMAS DAY COMPANY, OF SAN FRANCISCO, CALIFORNIA, A CORPORATION OF CALIFORNIA.

ELECTRIC OUTLET FIXTURE.

Application filed November 25, 1921. Serial No. 517,444.

To all whom it may concern:

Be it known that I, WILFRED B. GODDARD, a citizen of the United States, and a resident of the city and county of San Francisco, State of California, have invented a certain new and useful Electric Outlet Fixture, of which the following is a specification.

This invention relates to electric appliances and more particularly to an electric outlet fixture adapted to be arranged upon a suitable support in a pendant position to provide for the facile attachment to the fixture of an extension cord plug or other complementary part.

An object of the present invention is to provide an ornamental concealing shell to enclose an electric outlet connection and its complementary plug attachment so that the connection and plug, when in service, are substantially concealed from view and the whole forms an ornamental combined outlet when attached to a suitable support, as an electrolier or a wall bracket from which the device may be suspended in the pendant position and be readily accessible for the attachment and the removal of the plug to the outlet. The shell is constructed and arranged also to substantially conceal the outlet fixture when the plug has been removed.

A further object of the invention is to provide an ornamental, sectional shell, the leaves or sections of which are so connected and arranged as to be readily moved to an open uncovering position to expose the concealed or partially concealed outlet connection and permit the ready attachment of the complementary plug without the necessity of removing any of the parts of the fixture.

Another object is to provide for the connection of the shell sections or "leaves", as they may be called, so that they can be readily swung to the open position and so held while the plug is being attached to the fixture.

The invention possesses other objects and features of advantage, some of which, with the foregoing, will be made manifest in the following description of the preferred form of the invention, which is illustrated in the drawings accompanying and forming part of the specification. It is to be understood that it is not intended to limit the invention to the embodiment shown by the said

drawings and description, as variations may be adopted within the scope of the invention as set forth in the claims.

Figure 1 is a side elevation of the improved outlet device, shown as attached to the bottom of an electrolier.

Fig. 2 is a vertical, sectional view showing the enclosed outlet connection and the applied plug in dotted lines.

Fig. 3 is a longitudinal section, vertically through a modified form of the device.

The device of the present invention may be embodied in a variety of ornamental structures which will enable the attachment of the device to any suitable electrolier or bracket, this being accomplished, as by the provision of a shank or stem-like body 2, the upper end of which is provided with an eye 3, to be fastened in any desired manner to the part from which it is to be suspended. Upon the lower end of the shank there is suitably arranged a common or other form of electric outlet connection 4, this being secured, as by screws 5, or otherwise, to the forked lower end of the shank 2. The crotch of the fork provides for the clearance of the usual service wires entering the top of the outlet connection 4 and which wires are not shown.

It is desirable to substantially conceal the outlet connection, especially when it forms a part of an electrolier or ornamental wall bracket or portable or other lamp. To that end I have provided a shell consisting of any suitable number of leaves or sections 6, which may, for instance, be of concavo-convex, leaf-like form providing, when closed, a bulbous shell snugly covering the outlet 5.

In Figs. 1 and 2 of the drawings the leaves or sections are each provided at their upper ends with an eye or hook 7 and each of these is passed through a respective perforated or other bearing lug or part 8, at the upper end of the stem 2, and of which a number is provided equal to the number of the shell sections. This obviously permits the shell sections to hang in a freely pendant position, so that they may be readily spread open at their lower ends to permit the application of a plug P, shown applied in dotted lines, in Fig. 2, and in full lines in removed position. As soon as the plug has been applied, the leaf-like sections are released and fall to closed position,

substantially concealing the outlet and its attached plug.

A variation of the construction is shown in Fig. 3, wherein the leaf sections 6 are provided, somewhat below their upper ends, with pivots 6^a provided on the shank or stem 2; the upper ends of the sections 6, spreading outwardly somewhat, so that when they are closed together between the finger and thumb of one hand, the lower ends of the sections are spread open to uncover the outlet and permit the attachment of the plug, after which the handle-like upper ends of the sections 6 are released and the sections automatically closed together.

From the above it will be seen that I have provided an extremely simple and inexpensive type of highly ornamental outlet connection for electrical appliances and have eliminated the use of any wholly detached parts that are so likely to become lost or misplaced.

Preferably, that form of the device which comprises hinged leaves will have a pair of the leaves which form together a complete shell, as shown in Fig. 3.

What is claimed is:

1. A pendant electric outlet fixture consisting of a longitudinally split shell, the

shell sections being movable to provide access to the interior of the shell, and an outlet connection combined with the shell, the shell sections being normally gravitally positioned to conceal the connection.

2. A pendant outlet fixture comprising a plurality of pendant shell sections normally gravitally positioned to form a substantially closed shell and an electric outlet disposed within the shell and concealed by the pendant sections.

3. A pendant outlet fixture comprising a head, a plurality of pendant shell sections pivoted to said head, the sections being normally gravitally positioned to form a substantially closed shell and an electric outlet secured to said head and disposed within said shell and concealed by said sections.

4. An electric, outlet fixture consisting of a set of pendant, shell forming sections, means to which the sections are pivotally attached, and an outlet connection combined therewith; the sections having portions extending above their pivots so that said portions may be pressed toward each other to open the sections.

In testimony whereof, I have hereunto set my hand.

WILFRED B. GODDARD.
